UNITED STATES PATENT OFFICE.

ARTHUR H. NEWTON, OF NEW YORK, N. Y.

FUEL-MIXING DEVICE FOR INTERNAL-COMBUSTION ENGINES.

1,195,254.

Specification of Letters Patent. Patented Aug. 22, 1916.

Application filed March 1, 1916. Serial No. 81,506.

To all whom it may concern:

Be it known that I, ARTHUR H. NEWTON, a citizen of the United States, residing at 173 West Eighty-third street, New York, in the county of New York and State of New York, have invented certain new and useful Improvements in Fuel-Mixing Devices for Internal-Combustion Engines, of which the following is a specification.

This invention relates to fuel-mixing devices for internal combustion engines, particularly of the type designed for insertion within the intake-pipe of the engine, and having an annular flange or collar held between the meeting-flanges of the carbureter and manifold.

Attempts have been heretofore made to devise a mixer of this type having blades, stationary or rotatable, for imparting a whirling movement to the mixture of gasoline and air after it leaves the carbureter, screens of various sorts being sometimes employed to assist in the mixing of the fuel. Most of these, however, if not all, have been for one reason or another unsuccessful, and none of them so far as I know has attained sufficient success to warrant adoption by any of the leading makers of automobiles, in which a device of this character is particularly useful.

The object of the present invention is to produce a mixer of the aforementioned type, economical of manufacture and yet highly efficient; one that will be sufficiently substantial to withstand any back-firing and therefore protect the carbureter, and yet so constructed as to allow passage therethrough of the fuel-mixture with the least possible resistance; and one so designed as to insure complete and therefore uniform mixing of the air and gas before passing into the cylinders.

The invention is illustrated in the accompanying drawing, wherein,

Figure 1 is a side elevation of a preferred form of mixer; Fig. 2 is a vertical sectional view of the same, the rotatable vane and its spindle, however, being shown in elevation; Fig. 3 is a bottom view; Fig. 4 is a plan view of the vane or propeller; Fig. 5 is an elevation of the wire coil; and Fig. 6 is a side elevation of a mixer having a screen slightly modified in shape.

As illustrated, the mixer comprises a casting or shell 1, preferably of brass, having an annular upright portion 2, and an aper-

tured base 3 constituting the bottom of the device and conveniently formed of cross-bars 4 (see Fig. 3). The base 3 is provided with an annular flange or collar 5 by means of which the mixer may be held in the intake passage, the flange 5 being secured between the meeting-flanges of the carbureter and the manifold, not shown. Extending vertically upward from the base or spider 6 formed by the cross-bars 4, and integral therewith if the shell is cast, as is preferred, there is a bearing 6, preferably somewhat elongated, as shown.

Over the shell 1, and secured thereto along its lower edge preferably by a clamping-ring 7, there is a relatively fine-mesh screen 8, preferably of brass. The upper, outer edge of the portion 2 may be cut away to accommodate the lower edge of the screen 7 and its clamping-ring 7, as shown, the arrangement being such that the outer face of the ring 7 lies substantially flush with the outer surface of the upright portion 2 of the shell. The screen is dome-shaped and preferably, as shown in Figs. 1 and 2, substantially hemispherical, it having been found that screens having such shapes are noticeably more rigid and stronger, and therefore better able to withstand back-firing strains than screens of other shapes. A screen 8' shaped as shown in Fig. 6 may be used with good results, but is not quite so strong as that illustrated in Figs. 1 and 2.

A spindle 9 is mounted for easy rotation in the elongated bearing 6, and is provided at its upper end, beyond the bearing, with a propeller 10, the several blades of which extend outwardly to within a short distance of the shell 1. The lower end of the spindle 9 may be provided with a nut or other head 11.

Within the casing 1 and its screen-cover 8, and so formed as to lie loosely against the inner surfaces thereof, there is a wire coil 12, the height of which, when the parts are assembled, is substantially that of the inside of the casing and its screen-top.

The use of the device will be apparent. The shell or casing is slid up into the intake-pipe of the engine preferably where the carbureter-flange abuts the same, the flange 5 of the mixer being securely held between the meeting-flanges of the carbureter and the manifold. As the mixture of air and hydrocarbon passes into the shell of the mixer, it is divided by the spider 4 into sev-

eral portions which, upon further forward movement impinge upon the blades of the propeller 10 and cause the latter to rotate quite rapidly in a well-known manner, the mixture becoming well broken up and part thereof being thrown outward against the wire coil 12 and the casing and there further broken up and mixed. The portion of the mixture which passes upward through the blades of the propeller strikes the wire coil 12 and immediately thereafter the wire-screen 8, both of these elements assisting materially in the mixing of the ingredients of the charge.

The coil 12 not only assists in the mixing operation, as above described, but serves likewise, due perhaps to any movement it may receive from the impact of the fuel in passing thereby, to keep the inner surface of the casing clean and free from any foreign accumulations whatsoever. After use, it has been observed that both the inner wall of the shell and the wire coil are clean and bright. The wire coil also serves as a reinforcement of the screen-top 8, assisting the latter to withstand any reverse shocks due to back-firing.

With the use of a device of this construction, a very thorough mixing of the air and gas is effected, in proper proportions, viz., three parts air to one part of gasoline, without materially impeding the flow to the cylinders, and a great saving of gasoline is realized. Since, as is well known, back-firing is frequently due to improper mixing of the air and hydrocarbon, it will be appreciated that the device of the present invention will prove of considerable advantage in the elimination of this evil. Carbon deposits in the cylinders due to use of low-grade gasoline, or faulty mixing, or accumulation of dust, dirt, etc., will also be prevented.

I claim:—

1. A fuel-mixing device for internal combustion engines, comprising a casing having an annular upright portion for insertion in the intake-pipe of the engine and a flanged, apertured support forming the bottom of the device; a central bearing in said support; a rotatable spindle journaled in said bearing; blades on said spindle; a dome-shaped screen cap secured along its lower edge to said casing; and a wire coil within the cap and casing and lying thereagainst.

2. A fuel-mixing device for internal combustion engines, comprising a casing having an annular upright portion for insertion in the intake pipe of the engine and a flanged, apertured support forming the bottom of the device; a central bearing in said support; a rotatable spindle journaled in said bearing; blades on said spindle; a substantially hemispherical screen cap having a flush connection along its equatorial line with said casing; and a wire coil within the cap and casing and lying thereagainst.

3. A fuel-mixing device for internal combustion engines, comprising a casting having an annular upright portion for insertion in the intake-pipe of the engine; a flanged, apertured support forming the bottom of the device and a central bearing in said support; a rotatable spindle journaled in said bearing; blades on said spindle; a substantially hemispherical screen cap having a flush connection along its equatorial line with said casting; and a wire coil within the cap and casting and lying thereagainst.

In testimony whereof I affix my signature in presence of two witnesses.

ARTHUR H. NEWTON.
